UNITED STATES PATENT OFFICE.

PAUL GÜNGERICH, OF BERLIN-STEGLITZ, GERMANY, ASSIGNOR, BY MESNE ASSIGNMENTS, TO ALIEN PROPERTY CUSTODIAN.

MEANS FOR SAFEGUARDING AGAINST FIRE AND EXPLOSION.

1,321,799.

Specification of Letters Patent. Patented Nov. 11, 1919.

Application filed June 28, 1913. Serial No. 776,325.

To all whom it may concern:

Be it known that I, PAUL GÜNGERICH, a citizen of the Empire of Germany, and resident of Berlin-Steglitz, Germany, have invented certain new and useful Improvements in Means for Safeguarding Against Fire and Explosion, of which the following is a specification.

My invention relates to improvements in means for safeguarding against fire and explosion, closed vessels in which materials or articles are treated with inflammable liquids in the presence of a protective gas. More particularly my invention relates to improvements in means described and claimed in my copending application for patent filed March 26, 1913 Serial Number 757,037. The object of the improvements is to provide an apparatus, whereby the economy of the operation is greatly increased.

In the means described in my aforesaid prior application the protective gas which is used in each operation is lost by escaping at the end of the operation into the atmosphere after opening the cover of the vessel in which it is used or after removing the same by means of the suction pump connected with the said vessel. In order to increase the economy the protective gas within the working vessel, or the mixture of the said protective gas with air is conveyed by a pump into a gas receptacle from which it is taken again for further use. In carrying out the method described in the aforesaid application for patent the working vessel always contains a mixture of the protective gas and air. Therefore when storing the said mixture and again using the same the amount of air in the mixture might gradually be increased to such an extent, that it is not suitable any more to provide a safeguard against fire and explosion. Therefore a further feature of my invention consists in providing means for admitting to the working vessel a definite amount of fresh gas, which amount is admitted at suitable periods and preferably at the end of each operation, and which is sufficient to safely prevent the formation of explosive gaseous mixtures. Thereby I am enabled to reduce the consumption of protective gas to a minimum and notwithstanding this to protect the working vessel in a reliable way.

For the purpose of better explanation an apparatus embodying my present invention

has been shown in the accompanying drawings, in which the same letters of reference have been used in all the views to indicate corresponding parts. In said drawings—

Figure 1, is a diagrammatical view of a system which is suitable for chemically cleaning clothes and the like, and

Fig. 2, is a diagrammatical view illustrating the different positions of the valves of the apparatus corresponding to different operations.

In the example illustrated in the drawings a washing machine or vessel 2 is closed in a gas tight way by a door 1, and it is equipped with fast and loose pulleys 3 and 4 by means of which a perforated drum (not shown) located inside the vessel can be rotated. To allow of the benzin being used over and over again, for example for cleaning clothes, a pure benzin receptacle 5, a semi-pure benzin receptacle 6, and a soiled benzin receptacle 7 are provided. The receptacles 5 and 6 are connected by pipes 8 and 9 with a tank containing a protective gas. This tank is not shown in the drawings. The protective gas which is admitted to the receptacles is under a pressure sufficient to force the benzin contained within the receptacles through the pipes 10 and 11 and into the washing vessel 2. The pipes 10 and 11 are equipped with shut-off devices or valves 13 and 14 which are controlled (that is, either locked or released) by a suitable device, which may consist of a swinging or pivoted member 55' which in one position prevents, and in another position permits, the operation of said valves. The soiled benzin receptacle 7 is connected by a pipe 15 with the gas chamber of a gasometer 16 which is used in my improved method for storing the protective gas coming from the washing receptacle 2 and adding thereto a fresh supply of protective gas to make it suitable for further use.

From the pipe 15 a pipe 90 is branched off which is connected through a three-way cock valve 91 with a pipe 92 connected to a tubular stud 93 of the washing receptacle 2. The pipe 92 is provided with a back pressure valve 94 the purpose of which is described hereinafter. The three-way valve 91 is connected with a casing 23 within which a locking device is located. The said locking device consists of two valve disks 25 and 26 secured to a stem 24 and co-operating with

the valve seats provided on the upper and lower sides of a sleeve 27. The stem 24 of the pressure member is acted upon by a weight 29, and it is adapted to engage with 5 its lower end within one of the ways of a threeway valve cock 95 located below the casing 23. The threeway valve 95 is located in a pipe 96 branched off from the pipe 9 for the protective gas and communicating with 10 an intermediate receptacle 98. The threeway valves 91 and 95 are positively connected with each other by a gearing 97. The intermediate receptacle 98 is connected at its 15 top with the pipe 92 through a pipe 100 containing a two-way valve 99, and at its bottom with the pipe 90 for the protective gas through a pipe 102 equipped with a two-way cock valve 101. The valves 99 and 101 are operatively connected with each other 20 by a rod 103, and the valve cock 99 is connected by a rod 104 with bevel gear-wheels 55 and 56 connected with the locking member 55'. The said bevel gear wheels 55 and 56 are connected by a rod 105 with a locking 25 device 106 acting on the operating mechanism 3, 4 of the washing machine 2. To the top of the washing machine 2 a pipe 31 is connected which opens into the atmosphere and is equipped with a two-way cock valve 30. Below the said cock valve a pipe 34 is branched off from the pipe 31, which is connected to the suction pipe of an air pump 32. The pressure pipe 107 of the pump 32 is 35 equipped with a two-way cock valve 108 and connected with a pipe 109, 110, the branch 109 opening into the atmosphere and the branch 110 being connected with gas pipes 15 and 90.

The washing receptacle 2 is provided at 40 its bottom with an outlet pipe 39 which is connected through a two-way valve cock 35 with a pipe 36 communicating with the semi-pure benzin receptacle 6, and through a two-way cock valve 37 with a pipe 38 communicating with the soiled-benzin receptacle 7. The cock 35 is positively connected by a rod 45 111 with a three-way cock valve 112 which is provided at the joint of the pipes 9 and 92.

In the example described herein the closing members 95, 101, 30, and 108 are operated 50 in the proper order corresponding to the steps of the method from a common shaft 42 by cams 113, 114, 84, and 115. The shaft 42 is furthermore provided with a cam disk 55 116 which is adapted to operate through a lever 117 a member 119 arranged to throw the driving mechanism 118 of a suction pump 32 into or out of operation.

The operation of the apparatus described 60 herein is as follows:

Fig. 1 shows the parts of the apparatus in the position which they occupy when starting the operation. The interior of the washing receptacle or machine 2 is closed as 65 against all the gas and liquid pipes connect-

ed therewith as well as against the atmosphere, and it communicates exclusively with the air pump 32 through the pipe 34. The driving mechanism 118 of the said pump is in operative position, so that the pump 70 draws the air out of the receptacle 2 and conveys the same through the pipes 107 and 109 into the atmosphere. As soon as sufficient suction has been produced within the washing machine 2, which suction is transmitted through the pipes 93 and 92 to the casing 23 inclosing the locking mechanism, the locking members 24, 25, 26 is lifted, because the pressure of the protective gas passing from the intermediate casing 98 and 75 through the pipe 96 into the casing 23 comes into action. Thereby the valve disk 26 is seated, and closes the opening 27, as has been indicated in Fig. 1 in dotted lines, and simultaneously the three-way cock 95 is disengaged by the stem 24, so that when rotating the cam disk 113 the cock 95 and the cock 91 positively connected therewith are shifted into the position II shown in Fig. 2, the other cocks remaining in their positions. 80

Now fresh protective gas flows from the pipe 9 and through the pipe 96 into the intermediate casing 98. Simultaneously the suction acting on the valve disk 25 of the locking devices 24, 25, 26 is removed by protective gas flowing from the receptacle 16 through the pipes 15 and 90 into the upper chamber of the casing 23. Thereby the locking member is moved downward into the position shown in Fig. 1, and it locks 95 the three-way cock valve 95 in the position II. As soon as the pressure of the fresh protective gas admitted to casing 98 through pipe 96, which pressure is operative also in the lower chamber of the casing 23, 100 is in excess of the pressure of the protective mixture flowing through the pipe 90 and acting on the valve disk 25, which pressure is comparatively small, the locking members 24, 25, 26 is again lifted and the 105 cock 95 unlocked.

Now after a further rotation of the shaft 42 the valves assume the position III shown in Fig. 2, in which the valves 95 and 91 are again in the positions shown in Fig. 1, while 115 the valves 101 and 99 are turned in such a way, that the protective gas inclosed within the intermediate receptacle 98 can flow through the pipes 100, 92, and 93 into the washing vessel 2, while another supply of 120 fresh gas from the gasometer 16 flows into the intermediate receptacle 98 through the pipes 15, 90, and 102, so as to complete the filling of the protective gas within the washing vessel 2. Simultaneously by the proper position of the cam disk 116, the lever 117 coöperating therewith, and the member 119 for throwing the driving mechanism 118 of the air pump into or out of operation, the said driving mechanism is stopped. 125

When the valves assume the position III the valves 13 and 14 which are located in the benzin supply pipes 10 and 11 are unlocked by the rod 104, so that now successively 5 opening the valve 14 and the valve 13 by hand at first semi-pure benzin and afterward pure benzin is admitted through the pipes 11 and 10 respectively into the washing machine 2. Furthermore by means of 10 the rod 105 the locking member 106 of the driving mechanism 3, 4 of the washing machine is thrown out of operation, so that the perforated drum provided within the washing machine is thrown into operation. 15 At the end of the washing operation the outlet valve 37 is opened and the soiled benzin is withdrawn through the pipes 39 and 38 and into the receptacle 7. Thereupon, after closing the cock 37 and opening 20 the valve 13 pure benzin is admitted to the washing receptacle for rinsing the clothes inclosed therein, whereupon after opening valve 13 the semi-pure benzin is transmitted to the semi-pure benzin receptacle 6. As the cock 35 is positively connected with the three-way cock 112 by the gearing 111, the pressure between the gas chamber of the receptacle 6 and the hollow 25 of the washing vessel 2 is equalized, a flow 30 of compressed gas from the pipe 92 to the casing 23 being prevented by the back pressure valve 94.

At the end of the washing and rinsing operations the valves assume the positions 35 indicated by the numeral IV, in which the interior of the washing vessel is connected exclusively with the air pump 32, and the cock 108 is set in such a position, that the pump 32 can draw the protective mixture 40 from the interior of the washing vessel and force the same through the pipes 110 and 15 into the gasometer 16.

After the protective gas has been drawn off, the shaft 42 is turned a further step into 45 the position indicated by the numeral V. Now air has access to the washing vessel through the cock 30, whereupon the door 1 can be opened for removing the cleaned goods from the vessel. In this position the 50 driving mechanism 118 of the air pump is in its inoperative position.

For each operation the shaft 42 is turned through an angle of 72 degrees.

While in describing the invention reference has been made to a particular example embodying the same, I wish it to be understood, that my invention is not limited to the apparatus shown in the drawings, and that various changes may be made in the 60 general arrangement of the apparatus and the construction of its elements without departing from my invention.

I claim herein as my invention:

1. The combination of a vessel adapted to 65 be closed to the surrounding air, means for

supplying a cleaning liquid to said vessel, a storing receptacle adapted to receive the protective gas from said vessel, a connection for conveying protective gas from said receptacle to said vessel, and separate means 70 for conveying an additional supply of protective gas to said vessel.

2. The combination of a vessel adapted to be closed to the surrounding air, means for supplying a cleaning liquid to said vessel, an intermediate receptacle adapted to be filled with a protective gas and to be connected with said vessel, a connection for supplying protective gas to said intermediate receptacle, a storage receptacle adapted to 75 deliver protective gas to said connection, means for withdrawing protective gas from said vessel and conveying it to said storage receptacle, and a connection other than the one that leads from the storage receptacle, to supply fresh protective gas to said intermediate receptacle.

3. The combination of a vessel adapted to be closed to the surrounding air, means for supplying a cleaning liquid to said vessel, a storage receptacle for a protective gas, adapted to receive protective gas from said vessel and to return said gas to such vessel, and separate means for conveying an additional supply of protective gas to said vessel. 90

4. The combination with a vessel adapted to be closed to the surrounding air, and means for supplying an inflammable liquid for said vessel, of a storing receptacle adapted to receive the protective gas from said vessel, means to supply protective gas from said storing receptacle to said vessel, and a protective gas supply connection other than the one that leads from the storing receptacle for the protective gas, to supply fresh 105 protective gas to said vessel.

5. The combination with a vessel adapted to be closed to the surrounding air, and means for supplying an inflammable liquid for said vessel, of means for supplying a 110 protective gas adapted to be connected with said vessel to convey fresh gas thereto, a storing receptacle adapted to receive the protective gas from said vessel, and means to supply protective gas from said storing 115 receptacle together with a fresh supply of protective gas to said vessel.

6. The combination with a vessel adapted to be closed to the surrounding air, and means for supplying an inflammable liquid 120 for said vessel, of a storing receptacle adapted to receive the protective gas from said vessel, an intermediate receptacle adapted to receive protective gas from said storing receptacle, a protective gas supply connection 125 other than the one that leads from the storing receptacle for the protective gas, for supplying fresh protective gas to said intermediate receptacle, means to connect said intermediate receptacle with said vessel and storing 130

4
receptacle and to disconnect the same from the said fresh gas supplying connection, and means to cause a flow of protective gas from the storing receptacle to the intermediate receptacle and from the intermediate receptacle to the vessel.

7. The combination with a vessel adapted to be closed to the surrounding air, means for supplying an inflammable liquid to said vessel, and means to produce a vacuum within said vessel, of means for supplying a protective gas, a storing receptacle adapted to receive the protective gas from said vessel, an intermediate receptacle adapted to be connected with said protective gas supplying means, vessel and storing receptacle, a casing inclosing a locking member controlled by the fluid pressure within the casing, a three-way cock controlling the connection of said protective gas supplying means, intermediate receptacle and casing, a three-way cock controlling the connection of said casing with the vessel and storing receptacle and located at the side of the locking member within the casing opposite to the cock controlling the connection of said protective gas supplying means, intermediate receptacle and casing, said cocks being operatively connected with each other and adapted to be locked by said locking member within the casing, valves controlling the connection of said intermediate receptacle with said vessel and storing receptacle, and operating means for said cocks and valves.

35 8. The combination with a vessel adapted to be closed to the surrounding air, means for supplying an inflammable liquid to said vessel, and means to produce a vacuum within said vessel, of means for supplying a protective gas, a storing receptacle adapted to receive the protective gas from said vessel, an intermediate receptacle adapted to be connected with said protective gas supplying means, vessel and storing receptacle, a casing inclosing a locking member controlled by the fluid pressure within the casing, a three-way cock controlling the connection of said protective gas supplying means, intermediate receptacle and casing, a three-way cock controlling the connection of said casing with the vessel and storing receptacle and located at the side of the locking member within the casing opposite to the cock controlling the connection of said protective gas supplying means, intermediate receptacle and casing, said cocks being operatively connected with each other and adapted to be locked by said locking member within the casing, valves operatively connected with each other and controlling the connection of said intermediate receptacle with said vessel and storing receptacle, and operating means for said cocks and valves.

60 9. The combination with a vessel adapted to be closed to the surrounding air, means

for supplying an inflammable liquid to said vessel, a shut-off valve in said supplying means, locking means for said shut-off valve, and means to produce a vacuum within said vessel, of means for supplying a protective gas, a storing receptacle adapted to receive the protective gas from said vessel, an intermediate receptacle adapted to be connected with said protective gas supplying means, vessel and storing receptacle, a casing inclosing a locking member controlled by the fluid pressure within the casing, a three-way cock controlling the connection of said protective gas supplying means, intermediate receptacle and casing, a three-way cock controlling the connection of said casing with the vessel and storing receptacle and located at the side of the locking member within the casing opposite to the cock controlling the connection of said protective gas supplying means, intermediate receptacle and casing, said cocks being operatively connected with each other and adapted to be locked by said locking member within the casing, valves operatively connected with each other and controlling the connection of said intermediate receptacle with said vessel and storing receptacle, an operative connection between said controlling valves and shut-off valve, and operating means for said cocks and valves.

10. The combination with a vessel adapted to be closed to the surrounding air, a member within said vessel, operating means for said member, locking means for said operating means, means for supplying a protective gas, a storing receptacle adapted to receive the protective gas from said vessel, an intermediate receptacle adapted to be connected with said protective gas supplying means, vessel and storing receptacle, a casing inclosing a locking member controlled by the fluid pressure within the casing, a three-way cock controlling the connection of said protective gas supplying means, intermediate receptacle and casing, a three-way cock controlling the connection of said casing with the vessel and storing receptacle and located at the side of the locking member within the casing opposite to the cock controlling the connection of said protective gas supplying means, intermediate receptacle and casing, said cocks being operatively connected with each other and adapted to be locked by said locking member within the casing, valves operatively connected with each other and controlling the connection of said intermediate receptacle with said vessel and storing receptacle, an operative connection between said controlling valves, shut-off valve and locking means and adapted to throw the locking means into locking position while protective gas is being transmitted into the vessel, and operating means for said cocks and valves.

11. The combination with a vessel adapted to be closed to the surrounding air, means for supplying an inflammable liquid to said vessel, and means to produce a vacuum within the vessel, of means for supplying a protective gas adapted to be connected with said vessel, a storing receptacle adapted to receive the protective gas from said vessel, means to supply protective gas from said storing receptacle to said vessel, and interdependent means for controlling said supplying means and said vacuum producing means to throw the latter out of operation.

12. The combination with a vessel adapted to be closed to the surrounding air, means for supplying an inflammable liquid to said vessel, and means to produce a vacuum within the vessel, of means for supplying a protective gas adapted to be connected with said vessel, a storing receptacle adapted to receive the protective gas from said vessel, means to supply protective gas from said storing receptacle to said vessel, means to open said vessel to the surrounding air, and interdependent means for controlling said opening means and said vacuum producing means to throw the latter out of operation.

13. The combination with a vessel adapted to be closed to the surrounding air, means for supplying an inflammable liquid to said vessel, and means to produce a vacuum within said vessel, of means for supplying

a protective gas, a storing receptacle adapted to receive the protective gas from said vessel, an intermediate receptacle adapted to be connected with said protective gas supplying means, vessel and storing receptacle, a casing inclosing a locking member controlled by the fluid pressure within the casing, a three-way cock controlling the connection of said protective gas supplying means, intermediate receptacle and casing, a three-way cock controlling the connection of said casing with the vessel and storing receptacle and located at the side of the locking member within the casing opposite to the cock controlling the connection of said protective gas supplying means, intermediate receptacle and casing, said cocks being operatively connected with each other and adapted to be locked by said locking member within the casing, a back pressure valve located in the connection between the vessel and casing, valves controlling the connection of said intermediate receptacle with said vessel and storing receptacle, and operating means for said cocks and valves.

In testimony whereof, I have hereunto set my hand in the presence of the subscribing witnesses.

PAUL GÜNGERICH.
